UNITED STATES PATENT OFFICE.

EDWARD EVERETT HAYDEN, OF WASHINGTON, DISTRICT OF COLUMBIA.

AUTOMATIC ELECTRIC FIRE-ALARM SIGNAL.

No. 880,662.

Specification of Letters Patent.

Patented March 3, 1908.

Application filed May 11, 1906, Serial No. 316,363. Renewed July 2, 1907. Serial No. 381,925.

To all whom it may concern:

Be it known that I, EDWARD EVERETT HAYDEN, a citizen of the United States, residing at Washington, in the District of Columbia, have invented certain new and useful Improvements in Automatic Electric Fire-Alarm Signals; and I do hereby declare the following to be a full, clear, and exact description of the invention, such as will enable others skilled in the art to which it appertains to make and use the same.

My invention relates to improvements in automatic electric fire alarm signals, and the object of my invention is to produce a simple device of this type, which under ordinary circumstances may be used just like the common electric push button, but which when heated, automatically closes the circuit giving an alarm.

With this object in view my invention consists in the construction and combination of parts as hereinafter described and claimed.

In the accompanying drawings Figure 1 is a face view of my complete device; Fig. 2 is a similar view with the outer casing removed, and the outer contact arm broken away to show the inner contact arm; Fig. 3 is a side view of the device under ordinary circumstances, the outer casing being removed; Fig. 4 is a similar view showing the same expanded under the influence of heat, the outer contact arm being shown in dotted lines; Fig. 5 is an enlarged perspective view of the inner contact arm in its ordinary condition; and Fig. 6 is a longitudinal section of the device with the cover and push button removed.

a represents the backing, *b* the removable front casing, *c* the push button, *d* and *e* the circuit wires, and *f* the outer contact arm made in the form of a short spiral spring, all of these parts being of the usual construction. The outer casing *b* is adapted to screw upon the backing, screw threads *g* being provided for that purpose.

In the device shown in Fig. 3, the spring *f* is shown further away from the point *h* than would be the normal position when the button *c* is in place. The inner contact arm *h*, as shown in Fig. 2, is preferably made in a spiral form, so that in a small space considerable length of arm may be secured, and a corresponding increase of the bend or outward motion of the free end is secured when

heated. This inner contact arm *h* consists of two metal strips of different co-efficients of expansion brazed or otherwise secured together, the upper strip *i* being made preferably of steel, and the lower strip *j* of brass or other material having a higher coefficient of expansion than steel. A screw *k* is used to secure the contact *h* to the backing.

It will be obvious that under ordinary circumstances pushing on the button *c* will cause the arm *f* to contact with the point *h*, and thus the device may be used as an ordinary push button, while when it is subjected to a considerable degree of heat the brass on the inner contact arm expands more rapidly than the steel, bending the arm outwards and causing the point *h* to make electrical contact with the arm *f*, as shown in Fig. 4. The bend or expansion of the arm *h* is shown as exaggerated in Fig. 4, for the sake of clearness in the drawings.

It is preferable to have the inner contact arm *h* as the one to bend under the influence of heat because this arm is not acted upon by the push button, and furthermore, is next the wall or elevator shaft, and thus is more apt to get heated than the outer arm which is next the wood case *a*. But it will be evident that the outer spring may also be made of two metals, superimposed but in inverse order, and thus combine with the inner contact arm when heated. Thus both contact arms may be made to bend towards each other when heated, due to unequal expansion. Since the spiral *h* would bend in the reverse direction when subjected to low temperatures, the socket is cut away or indented to allow for such bending, as shown at *m*, Fig. 6.

It will be obvious that the circuit will continue to be closed as long as the spiral is maintained at the high temperature, but when the temperature falls again, as by putting out the fire, the circuit will be broken, and the bell will stop ringing.

Having thus described my invention, what I claim and desire to secure by Letters Patent of the United States, is:—

In an automatic electric fire alarm signal, the combination of a backing having a central hollowed out portion, a casing carrying a push button and adapted to be secured upon said backing, a contact member consisting of strips of brass and steel fastened

together curved into the form of a spiral and normally contained in said hollowed out portion, and a resilient contact member adapted to be pushed in by said push button, 5 or to be struck by said first named contact member as it expands under the influence of heat, substantially as described.

In testimony whereof, I affix my signature, in presence of two witnesses.

EDWARD EVERETT HAYDEN.
